UNITED STATES PATENT OFFICE.

BENJAMIN CRAWFORD, OF DANVILLE, ILLINOIS.

DESIGN FOR A FENCE-POST.

SPECIFICATION forming part of Design No. 32,964, dated July 17, 1900.

Application filed June 9, 1900. Serial No. 19,784. Term of patent 7 years.

To all whom it may concern:

Be it known that I, BENJAMIN CRAWFORD, of the city of Danville, county of Vermilion, and State of Illinois, have invented and produced a certain new Design for a Fence-Post, of which the following is a specification.

In the drawings forming part of this specification, Figure 1 is a perspective representation of my design. Fig. 2 is a plan of the upper surface of the base and post. Fig. 3 is a plan of the under surface of the base.

The base 1 is in general outline in the form of a frustum of a square-based pyramid; but the pyramidal form is made up of a set of generally-rectangular figures of constantly-decreasing proportions rising one above another, and the faces of the members of the base are vertically concaved. The base is hollowed from its bottom upward, and it may be described with reasonable accuracy as a frustum of a stepped square pyramid.

The post 2 is triangular in cross-section. It is hollow, and one of its faces is provided with a set of holes. The axis of the post forms a continuation of the axis of the base, at least 25 approximately, and one of the faces of the post is parallel with a face of the base.

The material features of the design are a base in the form of a frustum of a stepped square pyramid with concaved faces 30 surrounded by a post triangular in cross-section.

Having described my invention, what I claim as new, and desire to secure by Letters Patent, is—

The design for a fence-post, substantially 35 as shown and described.

In testimony whereof I sign my name in the presence of two subscribing witnesses.

BENJAMIN CRAWFORD.
